UNITED STATES PATENT OFFICE.

JOSEPH H. HUBER, OF PERU, INDIANA.

WORK-SUPPORT FOR CALCULATING-MACHINES.

1,335,239.

Specification of Letters Patent. Patented Mar. 30, 1920.

Application filed March 10, 1919. Serial No. 281,717.

To all whom it may concern:

Be it known that I, JOSEPH H. HUBER, a citizen of the United States, residing at Peru, in the county of Miami and State of Indiana, have invented certain new and useful Improvements in Work-Supports for Calculating-Machines; and I do declare the following to be a full, clear, and exact description of the invention, such as will enable others skilled in the art to which it appertains to make and use the same.

My invention has for its primary object to provide a simply constructed and inexpensive, yet a highly convenient and desirable work support to be used in connection with all sorts of calculating machines such as those employed in banking and book-keeping in all branches, the supporting shelf being provided with a pocket or pockets to receive the checks, deposit slips, or other slips of paper, in connection with which work has been performed upon the machine.

A further object is to provide each pocket with an inclined bottom and an approximately vertical wall at the lower end of such bottom, whereby the jarring of the checks or the like, by the vibration of the machine, will slide them downwardly against said vertical wall to maintain them in orderly fashion as they are stacked upon the bottom.

A still further object is to provide a supporting shelf having an area reserved adjacent each pocket upon which to stack the slips to be subsequently received in such pocket.

With the foregoing in view, the invention resides in the novel features of construction and unique association of parts, hereinafter fully described and claimed, the descriptive matter being supplemented by the accompanying drawing which forms a part of this application.

Figure 1 is an edge view of my invention applied to a calculating machine;

Fig. 2 is a top plan view;

Fig. 3 is a vertical section on the plane indicated by the line 3—3 of Fig. 2.

In the drawing above briefly described, the numeral 1 designates a flat horizontal shelf which is preferably but not necessarily of rectangular formation, said shelf being adapted to be connected to the frame or other part of a calculating machine in any preferred manner, and for illustrative purposes, I have shown said shelf hinged at 2 to the frame 3 of an adding machine 4, any

adequate means such as a brace rod 5, being provided for holding the shelf in horizontal position and for permitting the same to be lowered as shown in dotted lines in Fig. 1, 60 when its use is no longer needed. In the present arrangement, the brace rod 5 is pivoted as at 6 to the shelf 1 and the lower end of said rod is removably received in an opening 7 in part of the frame 3. By raising the shelf to the proper extent, the rod 5 is withdrawn from the opening 7, thus permitting the shelf to be lowered.

The shelf illustrated in the present application, is adapted for use in banks and has 70 two areas 8 and 9 reserved for checks 10 and deposit slips 11, and adjacent these areas 8 and 9, two pockets 12 and 13 are provided, said pockets being by preference located to the left of the aforesaid areas and 75 disposed obliquely for sake of convenience. The checks 10 will in most instances be stacked in a tray 14 having a bottom 15, a back 16 and one end wall 17, and this tray will rest upon the area 8. A similar tray 80 may be provided for the deposit slips 11, but in most instances this is unnecessary. As the amounts on the checks are listed upon the adding or other calculating machine 4, they are taken from the tray 14 and placed 85 in the pocket 12 and similarly, after each deposit slip has been listed, it is placed in pocket 13.

To maintain the checks and deposit slips in orderly fashion and thus prevent disarrangement thereof, each of the aforesaid pockets is provided with an inclined bottom 18 and an approximately vertical wall 19 at the lower end of such bottom. The parts 18 and 19 and two end walls 20 form the 95 pockets as clearly shown. As the checks 10, deposit slips 11, or other slips of paper, according to the use of the device, are stacked upon the bottoms of their respective pockets, the vibration of the calculating 100 machine causes them to slide downwardly against the approximately vertical wall 19 thus preventing disarrangement and insuring that they shall remain in orderly fashion.

As above suggested, the device is intended for installation upon all forms of machines, used in banking, bookkeeping, etc., and the arrangement and number of pockets may vary according to the use of the device. 110 For these reasons, I do not wish to be restricted to the exact details and arrangement

shown, and although the shelf is shown pivotally mounted for downward folding when not in use, it will be understood that it may well be mounted in any preferred manner.

5 I claim:

A work holder for calculating machines comprising a flat horizontal shelf disposed throughout its area in the same plane and having an area or areas near its right hand

10 edge reserved for slips in connection with which work is to be performed on the calculating machine, said shelf being provided at the left of each such area with a pocket

adapted to receive the slips after the work has been performed, each pocket having a 15 bottom inclining down to the left and an approximately vertical wall at the lower end thereof, whereby jarring of the slips, stacked on the bottom of the pocket or pockets, by vibration of the machine, will slide said 20 slips downwardly against said vertical wall to maintain them in orderly fashion.

In testimony whereof I have hereunto set my hand.

JOSEPH H. HUBER.
